UNITED STATES PATENT OFFICE.

ARTHUR C. HOUSE, OF WELDON, NORTH CAROLINA, AND GEORGE B. SCHEFFEY, OF WEEHAWKEN, NEW JERSEY.

FRAME FOR CLOTH BOARDS AND SIMILAR ARTICLES.

Application filed June 19, 1926. Serial No. 117,207.

Our invention relates to frames for cloth boards and similar articles. The type of cloth board for which these frames are intended is that in which the frame is of generally open structure, including side and end members, with or without one or more intermediate cross pieces, and is covered with a tightly applied tubular envelope which is usually paper of substantial thickness, this envelope covering the broad faces and longitudinal edges of the frame. In this type of board, if the frame is properly constructed and the envelope properly applied, they will mutually reinforce each other and produce a board or winder having great strength and stiffness and other desirable characteristics referred to later.

An important object of the invention is to provide a frame which is inherently very stiff and strong, and highly resistant to strains applied to it in the operation of winding fabric upon it or in handling the cloth bolt so produced, and is also especially adapted for co-operation with the paper envelope which additionally strengthens and reinforces the frame, in the manner above referred to.

Another object is to provide a frame of very simple structure and one composed of relatively cheap materials such as wood or wood and paper stock, and which may, for both of these reasons, be economically produced.

Another object is to provide a frame structure including side pieces of symmetrical and preferably round cross section, either tubular or solid, these side member being inherently exceedingly strong and stiff in proportion to the amount of material therein and also being especially adapted for simple and easy assembly with the cross pieces, either by hand operations or partly or entirely automatic machinery, one reason for this adaptability being the symmetrical cross sectional form of the members which admits of their application to the cross pieces in any rotative position.

Another object is to provide end cross-pieces of improved form, including end portions which overlap the ends of the side members and resist inward thrust applied by the chucks of the winding machine, these ends being contoured to match the semi-cylindrical contour of the side members, and the outer faces of the end cross-pieces be-

ing smooth, flat and flush to properly receive and maintain end labels in proper condition; and further, to provide improved interlocking formations on the end pieces and side members, which produce joints which are very stiff and resistant to angular deformation of the frame and are also devised to admit of easy and accurate assembly, either by hand or machine operations.

A particular object is to provide a structure which admits of the use, in certain cases, of tubular paper side pieces, which are probably the most economical devices that can be employed for this purpose, in connection with cross members of wood or analogous material, and to realize at the same time some or all of the other objects or advantages above and hereafter mentioned.

The characteristics and advantages of the invention are further sufficiently explained in connection with the following detail description of the accompanying drawing, which shows representative embodiments of the invention. After considering these examples, skilled persons will understand that many variations may be made, and I contemplate the employment of any structures that are properly within the scope of the appended claims.

In the drawings:

Fig. 1 is a perspective view of a frame embodying the invention in one form.

Fig. 2 is a fragmentary view, partly in section in the longitudinal central plane.

Fig. 3 is a plan view of a frame of modified structure.

Fig. 4 is a sectional detail thereof.

The invention contemplates the employment of side members 1, Fig. 1, or 1^a, Fig. 3, which are of symmetrical and preferably circular cross section, and which may be either of tubular section, as 1, or solid section, as 1^a; and which may be of paper or analogous fibrous composition, as 1, which represents a standard or special form of paper tube, which is a structure consisting of several turns or laminations of fibrous sheet material, such as chip board, pulp board or other "paper" stock, either straight-wound or spiral-wound, with suitable adhesive as a binder or strengthening material, or may be as at 1^a, of wood or analogous material.

In combination with such side members we employ cross pieces including the end pieces 2, Fig. 1, or 2^a, Fig. 3, and when necessary,

depending on the length of the frame, or other considerations, one or more intermediate cross pieces 3, Figs. 1 and 3. Desirably, these cross pieces are of wood or 5 analogous material, but in the broader aspect of the invention are not so limited, and may be of other material.

In each form of frame, the side and end members have connecting or interlocking 10 formations, which have generally similar characteristics in the two forms, but are specifically different. Thus, in both forms, the ends of the end pieces are semi-cylindrically rounded as at 4 to conform to the 15 semi-round formation of the side pieces, and these portions of the end members overlap the ends of the side pieces so that the smooth, rounded contour of the board edges in unbroken both along the side members and the 20 portions 4 of the end members, forming a smooth base for the envelope and the fabric wound thereon, which extends to the ends of the board, flush with the outer end surfaces 5 thereof. These outer surfaces are smooth 25 and flat, extending over the entire area of the board end, without any seam, groove or other interruption, and therefore provide a proper base for reception of end labels, which must be placed upon the boards by the 30 textile manufacturer or consumer to identify the nature or quality of the fabric. Especially, the overlapping ends 4 of the end pieces are firmly seated against the ends of the side members and resist any inward 35 strains applied to the end pieces. These boards are placed in winding machines which have chucks or holders which exert strong end pressure on the end pieces tending to 40 push them inward, and these strains are directly transferred by the end portions 4 to the ends of the side members and evidently the end pieces cannot be displaced inward 45 except by complete crushing of the side members, which are amply strong to resist the pressure.

When the cloth boards are so placed in the winding machine, they are revolved to wind the fabric on the board to form a bolt, and the fabric is placed under tension, which is often very considerable, involving severe 50 strains upon the board or its frame structure, and the present frames are amply strong and stiff to resist even the heaviest winding tension, as will sufficiently appear from further 55 description.

A common characteristic of the end and side piece connection in both forms of frame, is that the respective pieces have interfitting 60 formations, or dowel and socket formations, providing a strong and secure interlocking connection, and the end pieces also have wall 65 formations engaging substantial segments of the ends of the side members, to provide additional stiffness at the corner joints. Thus, in Figs. 1 and 2, the end pieces are cut (by a

suitable tool, such as a hollow bit) to provide integral dowels, these extending from annular shoulders 7 about the outer segments of the dowels, these shoulders continuing into part-cylindrical slots 8 separating the dowels from walls 9 of the end pieces, these walls being substantially semi-cylindrical and terminating in edges 10 which are flush with end segments of the side members. Otherwise stated, these edges 10 75 constitute ends of the inward portions of the flat faces 11, which are tangent to the surfaces of the side pieces. The dowels and the walls 9 are dimensioned to have a substantially tight sliding fit into and about the ends of the side members, as sufficiently understood in Fig. 2, so that the parts firmly interlock, and usually glue is applied before assembly, to insure permanent connection. When the parts are connected the dowels of 80 substantial length fitting in the side members and the bearing of the inner segments of the side members of substantial area, against walls 9, provide a very strong and stiff brace against angular or other distortion of the frame and board.

To facilitate assembly, desirably, the ends of the dowels are rounded or beveled as at 12, and the inner edges of walls 9 are also tapered or beveled as at 13, so that the tubular side members are easily and practically automatically guided into position in the assembling operation. This is especially important in assembling the parts with an automatic or other machine in which it is only 100 necessary to approximately position the respective parts, whereupon they are brought into proper engagement by inward movement of the end pieces in relation to the side members.

In the form shown in Figs. 3 and 4, where the side members are desirably of solid section, they are formed with end dowels 15, which are desirably more or less tapered as shown, these dowels being surrounded by 110 annular shoulders 16. The end pieces 2^a have the inner faces of their ends formed with flat circular areas 17 to co-operate with shoulders 16, the inner contour of these faces being defined by walls 18 of semi-cylindrical 115 form to co-operate with inner segments of the side members, as the walls 9 do in the previous example. Centrally in the circular formations 17, sockets 20 are provided, generally formed to fit the dowels 15 or somewhat deeper than the dowels. The dimension of the wall 18 lengthwise of the board is desirably greater than the length of the dowel 15, so that in assembling the parts the side members may be moved laterally until segments of the full-diameter end portions of these members engage inward segments of the walls 18, whereupon the dowels are aligned with the sockets 20 and the parts may then be fully interlocked by inward 120 125 130

movement of the end pieces in the lengthwise direction of the board, whereupon the dowels enter the sockets and segments of the full-diameter portions of the side members 5 are in engagement with walls 18 and the parts are braced against diagonal, twisting and other strains, as in the previous case. Glue is also usually applied to any or all of the engaging surfaces before they are 10 brought together.

The intermediate cross pieces 3 are not subject to strains causing displacement lengthwise of the board, and therefore it is sufficient to make their thickness equal to 15 the outer diameter of the side pieces and to provide in their ends, semi-cylindrical sockets 21 to fit the inner contours of the side members. Glue is also usually applied to 20 secure the cross members against accidental displacement.

While the dimension of the end members in the longitudinal direction of the frame, from the ends of the side members to the outer faces 5, or in other words, the longitudinal thickness of the end portions 4, may 25 vary, this dimension, as indicated at A, Fig. 2, is usually greater than would be necessary for the sake of structural strength, and may originally be, for example, as indicated at a' . This is to allow sufficient 30 thickness of the end pieces in the longitudinal direction of the board to provide for variations which often occur in the width of the cloth to be wound thereon. The width 35 of cloth frequently varies as much as $\frac{1}{2}$ ", amounting to $\frac{1}{4}$ " when the cloth is folded before winding, and the boards are usually 40 designed so that when full-width cloth is wound on them the edges of the cloth are flush with the end faces 5; but with the extra thickness provided, if the cloth runs narrower, narrow slabs of proper thickness may be cut off from the end pieces or one 45 of them, as indicated in full and dotted

lines, in Fig. 2. This enables the textile 45 manufacturer or finisher to easily conform the board length to variations in width of the fabric without keeping on hand a range of slightly-varying board size for this purpose.

As above stated, an important feature is the provision of the flat, smooth end faces 5 for the reception of end labels, and it will be noted that even when substantial slabs 50 are cut from the end pieces, as, and for the 55 reasons above mentioned, the smooth, continuous, flat surface for label reception is still maintained.

We claim:—

1. A frame for cloth boards or winders 60 comprising side members of symmetrical cross section and end members having portions overlapping ends of the side members and contoured to agree with the outer contour of the side members, the side and end 65 members also having interfitting dowel and socket formations, the end members also having segmental walls co-operating with substantial inward end areas of the side members to provide additional corner 70 bracing.

2. A frame for cloth boards or winders comprising tubular paper side members of substantial wall thickness and end members having portions overlapping ends of the 75 side members and contoured to agree with the outer contour of the side members, the side and end members also having interfitting dowel and socket formations, the end members also having segmental walls co-operating with substantial inward end areas 80 of the side members to provide additional corner bracing.

Signed at New York city in the county of New York and State of New York this 85 9th day of June, A. D. 1926.
